PRINTING MACHINE

Charles F. Dysert, Johnstown, Pa.

Application January 30, 1932. Serial No. 589,908

10 Claims. (Cl. 101—215)

This invention relates to printing machines of the hand operated type, the primary object of the invention being to provide a printing machine which will be small and compact and one which may be operated by persons unfamiliar with the art of printing, so that certain advertising matter such as pamphlets showing price lists or the like, may be readily printed.

An important object of the invention is to provide a device of this character constructed in such a way that the type used in forming the letters of the printed matter, may be positioned in the chase in the order in which letters are written in the formation of words, ignoring all principles carried out in the printing art, and used in type setting.

A still further object of the invention is to provide a printing machine using a transfer roller and a pressure roller, novel means being provided for automatically elevating the pressure roller from the transfer roller, upon the return movement of the transfer roller, after the machine has been operated to print, thereby preventing blurring of the printed matter transferred to the transfer roller.

With the foregoing and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is a plan view of a machine constructed in accordance with the invention.

Figure 2 is a longitudinal sectional view 40 through the machine.

Figure 3 is an end elevational view of the machine.

Figure 4 is a side elevational view of the machine, portions of the base being broken away.

Figure 5 is a sectional view taken on line 5—5 of Figure 3.

Figure 6 is a perspective view illustrating the construction of the type used with this machine.

Referring to the drawings in detail the reference character 5 designates the base of the printing machine, which is formed with parallel track sections 6, on which the carriage 7 operates, the carriage 7 being provided with wheels 8, so that the carriage may slide readily from one

end of the base to the other, during the printing operation.

As clearly shown by Figure 2 of the drawings, the carriage 7 is provided with a partitioning rib 8' disposed transversely thereof, the rib providing a compartment at one end of the carriage, for holding the chase 9 that carries the type, which are indicated by the reference character 10.

The type are of a novel construction, and embody an extension 11 and a head 12, the head 65 being substantially wide, so that portions thereof extend beyond the extensions 11 to the end that when the type are positioned, they may be positioned between the supporting bars of the chase, so that the heads thereof will contact with the 70 upper surfaces of the bars, thereby aligning the type.

Arranged at opposite sides of the carriage, are rack bars 13, which rack bars are engaged by the teeth 14, disposed at the ends of the transfer 75 roller 15, so that as the transfer roller is operated, movement will be transmitted to the carriage to move the chase and type carried thereby to a position directly under the transfer roller.

Arranged at points substantially intermediate 80 the ends of the base, and disposed at opposite sides of the base, are spaced uprights 16, which provide a bearing for the transfer roller, the shaft on which the transfer roller is mounted, being indicated by the reference character 17.

Coiled springs indicated at 18 exert a pressure 85 on the shaft 17, and normally act to hold the transfer roller downwardly.

At one end of the shaft 17, is mounted the pinion 19, which pinion meshes with the quadrant 20, which is mounted on the shaft 21, which in turn is rotated by means of the lever 22.

Thus it will be seen that due to this construction, rotary movement is transmitted to the transfer roller, by the operator moving the lever 22 95 forwardly and backwardly.

In connection with this movement, it might be stated that the ratio of teeth between the pinion 19 and quadrant, is such that with each complete movement of the quadrant, the transfer 100 roller will make a complete turn.

Disposed between the spaced uprights, and arranged near the upper ends, are bearing blocks 23 in which the ends of the shaft 24 are positioned, the shaft 24 providing the support for the pressure roller 25, which acts to press the sheet of paper being printed, into close engagement with the transfer roller, to cause the printed matter on the transfer roller to be transferred to the sheet.

During the operation of the machine, it is necessary for the pressure roller to be elevated, or raised out of contact with the transfer roller, with each reverse movement of the transfer roller, 5 and with this end in view, pivoted segments 26 are provided, which pivoted segments are mounted on the plates 27 which are formed with wide inner ends 28.

The pivot pins for the plates 27, and which are indicated by the reference character 29 secure the plates 27 to the ends of the transfer roller 15 and are so arranged with respect to the stops 30, that are also secured to the ends of the transfer roller, that the plates 27 may swing downwardly 15 to positions as shown by Figure 5 of the drawings, where the pivoted segments will move inwardly to positions spaced from the periphery of the transfer roller.

This operation takes place while the paper on 20 which the printing is to be transferred, is passing between the pressure roller and transfer roller, the paper passing from the transfer roller after the printing operation.

Upon reverse movement of the transfer roller, 25 the uppermost pivoted segment 26, will engage the pressure roller, and further movement of the transfer roller will cause the pivoted segments to swing on their pivots. Since the stops 30 restrict movement of the plates beyond a predetermined point, it will be seen that the segments are extended beyond the periphery of the transfer roller 15, or to positions as shown by Figure 4, wherein the outer edges of the segments will contact with the pressure roller elevating the pressure roller to prevent the smearing of the printed matter which has been transferred from the type 35 to the transfer roller.

Coiled springs 30' are mounted between the bearing blocks 23 and cross bars 31, there being 40 provided an adjusting screw 32 for adjusting the bearing blocks 23, thereby regulating the pressure directed to the pressure roller, by the coiled springs 30'.

The inking of the type, is accomplished through 45 the distributing rollers 32', that are mounted on the upstanding flanges 33, arranged at opposite sides of the base.

These distributing rollers receive ink from the ink roller 34 that operates above the rollers 32' in such a way that the peripheries of the rollers 32' contact with the periphery of the ink roller 34 to the end that ink is transferred from the roller 34 to the distributing rollers 32'.

A handle 35 is secured at one end of the roller 55 34, so that the roller 34 may be operated to distribute the ink placed thereon, over the rollers 32'.

In the operation of the device, the chase which has been set with type, is positioned on the carriage in a manner as described. The lever 22 60 is now swung forwardly in the direction of the arrow as indicated in Figure 4 of the drawings, whereupon the transfer roller is moved in a counter-clockwise direction.

The carriage together with the chase and the type, are moved to the right end of the machine with the result that the type prints on the transfer roller.

During this operation, the segments 26 contact with the pressure roller, moving the same upwardly out of contact with the transfer roller.

A sheet of paper to be printed is now fed between the transfer roller and pressure roller, and the lever 22 is reversed, causing printed matter to be transferred from the roller 15 to the sheet.

75 It is obvious that upon this reverse movement

of the lever 22, the segments 26 swing downwardly to positions as shown by Figure 5, allowing the pressure roller to move to contact with the transfer roller.

This operation is repeated, during the printing of each sheet.

I claim:

1. A printing machine comprising a base, a type supporting carriage movable longitudinally of the base, a transfer roller mounted on the base, a pressure roller operating above the transfer roller and contacting therewith for pressing a sheet to be printed into engagement with the transfer roller, means for automatically elevating the pressure roller during reverse movement of the transfer roller, and means for operating the transfer roller.

2. A printing machine comprising a base, a type supporting carriage movable longitudinally of the base for moving type under the transfer roller to transfer printed matter to the transfer roller, a pressure roller normally contacting with the transfer roller to press a sheet to be printed into engagement with the transfer roller, movable segments carried by the transfer roller for engaging the pressure roller to raise the pressure roller out of contact with the transfer roller during one movement of the transfer roller, and means for operating the transfer roller and carriage.

3. A printing machine comprising a base, a transfer roller mounted for rotary movement on the base, a type carriage movable longitudinally of the base, a pressure roller contacting with the transfer roller for pressing a sheet to be printed into engagement with the transfer roller, pivoted segments mounted on the transfer roller, means to hold the segments in their inactive positions during the printing operation, and means for holding the segments in an extended position to raise the pressure roller out of contact with the transfer roller, and means for operating the machine.

4. A printing machine comprising a base, a type supporting carriage movable longitudinally of the base, rack bars carried by the carriage, a transfer roller mounted on the base and having teeth engaging the rack bars to move the carriage longitudinally of the base as the transfer roller is operated, inking rollers for inking type carried by the carriage, a pressure roller contacting with the transfer roller for pressing a sheet of paper into engagement with the transfer roller, and means carried by the transfer roller for engaging the pressure roller to elevate the pressure roller to move the pressure roller out of contact with the transfer roller during one movement of the transfer roller.

5. A printing machine comprising a base, a transfer roller mounted for rotary movement on the base, a type carriage movable longitudinally of the base, and operating under the transfer roller to print on the transfer roller, a pressure roller operating above the transfer roller for pressing a sheet to be printed into engagement with the transfer roller, pivoted segments on the transfer roller, pivoted plates on which the segments are mounted, means engaging the plates for restricting movement of the plates and segments during one movement of the transfer roller, said plates adapted to swing to move the segments below the peripheries of the transfer roller upon movement of the transfer roller in the opposite direction, said segments adapted to contact with the pressure roller to elevate the pressure roller.

sure roller, and means for operating the transfer roller.

6. A printing machine comprising a base, a transfer roller mounted on the base, a type carriage mounted for movement longitudinally of the base, said carriage adapted to move under the transfer roller to transfer printed matter to the transfer roller, a pinion carried by the transfer roller, a segment contacting with the pinion 10 for rotating the pinion and transfer roller, a pressure roller operating above the transfer roller and adapted to press a sheet to be printed into engagement with the transfer roller, and means controlled by the movement of the transfer roller 15 for raising the pressure roller out of contact with the transfer roller during one movement of the transfer roller.
7. A printing machine comprising a base, a transfer roller mounted for rotary movement on 20 the base, a type carriage movable longitudinally of the base and operating under the transfer roller to print on the transfer roller, a pressure roller operating above the transfer roller for pressing a sheet to be printed, into engagement 25 with the transfer roller, and means controlled by the operation of the transfer roller for elevating the pressure roller out of contact with the transfer roller, for a predetermined period, during the rotation of the transfer roller.
8. A printing machine comprising a base, a rotary transfer roller mounted on the base, a type carriage movable longitudinally of the base and cooperating with the transfer roller in transferring printed matter onto the transfer roller, 30 35 a vertically movable pressure roller for pressing

a sheet onto the transfer roller, and means carried by the transfer roller and operated by the action of the transfer roller for elevating the pressure roller, at predetermined intervals.

9. A printing machine comprising a base, a transfer roller rotatably mounted on the base, a type carriage movable under the transfer roller for transferring printed matter to the transfer roller, a pressure roller operating above the transfer roller and adapted to press a sheet to be printed, into engagement with the transfer roller, pivoted members on the transfer roller, means on the transfer roller for moving the pivoted members into engagement with the pressure roller, raising the pressure roller out of contact with the transfer roller, when the transfer roller is rotated in one direction, and said pivoted members adapted to move to their inactive positions, upon reverse movement of the transfer roller.

10. A printing machine comprising a base, a transfer roller rotatably mounted above the base, a type carriage movable over the base and engaged by the transfer roller in transferring printed matter from the type carriage to a sheet to be printed, a vertically movable pressure roller mounted above the transfer roller for pressing a sheet into engagement with the transfer roller, pivoted members on the transfer roller and adapted to engage the pressure roller when the transfer roller is rotated in one direction, and 105 said pivoted members adapted to move to their inactive positions upon reverse movement of the transfer roller.
